CLAIM

The ornamental design for a security light, as shown and described.

DESCRIPTION

FIG. 1 is a front, right-side, top perspective view of a first embodiment of the security light with a portion of the unclaimed subject matter cut away to prevent visual obstruction of the claimed subject matter;

FIG. 2 is a front elevational view thereof;

FIG. 3 is a left side of a top plan view thereof split along the dot-dash match line, and with a portion of the unclaimed subject matter cut away to prevent visual obstruction of the claimed subject matter;

FIG. 4 is a right side of the top plan view thereof split along the dot-dash match line, and with a portion of the unclaimed subject matter cut away to prevent visual obstruction of the claimed subject matter;

FIG. 5 is a left-side elevational view thereof with a portion of the unclaimed subject matter cut away to prevent visual obstruction of the claimed subject matter, the right-side elevational view (not provided) being a mirror-image thereof;

(Continued)

FIG. 6 is a left side of a bottom plan view thereof split along the dot-dash match line, and with a portion of the unclaimed subject matter cut away to prevent visual obstruction of the claimed subject matter; and

FIG. 7 is a right side of a bottom plan view thereof split along the dot-dash match line, and with a portion of the unclaimed subject matter cut away to prevent visual obstruction of the claimed subject matter.

FIG. 8 is a front, right-side, top perspective view of a second embodiment of the security light with a portion of the unclaimed subject matter cut away to prevent visual obstruction of the claimed subject matter;

FIG. 9 is a front elevational view thereof;

FIG. 10 is a left side of a top plan view thereof split along the dot-dash match line, and with a portion of the unclaimed subject matter cut away to prevent visual obstruction of the claimed subject matter;

FIG. 11 is a right side of the top plan view thereof split along the dot-dash match line, and with a portion of the unclaimed subject matter cut away to prevent visual obstruction of the claimed subject matter;

FIG. 12 is a left-side elevational view thereof with a portion of the unclaimed subject matter cut away to prevent visual obstruction of the claimed subject matter, the right-side elevational view (not provided) being a mirror-image thereof;

FIG. 13 is a left side of a bottom plan view thereof split along the dot-dash match line, and with a portion of the unclaimed subject matter cut away to prevent visual obstruction of the claimed subject matter; and

FIG. 14 is a right side of a bottom plan view thereof split along the dot-dash match line, and with a portion of the unclaimed subject matter cut away to prevent visual obstruction of the claimed subject matter.

FIG. 15 is a front, right-side, top perspective view of a third embodiment of the security light with a portion of the unclaimed subject matter cut away to prevent visual obstruction of the claimed subject matter;

FIG. 16 is a front elevational view thereof;

FIG. 17 is a left side of a top plan view thereof split along the dot-dash match line, and with a portion of the unclaimed subject matter cut away to prevent visual obstruction of the claimed subject matter;

FIG. 18 is a right side of the top plan view thereof split along the dot-dash match line, and with a portion of the unclaimed subject matter cut away to prevent visual obstruction of the claimed subject matter;

FIG. 19 is a left-side elevational view thereof with a portion of the unclaimed subject matter cut away to prevent visual obstruction of the claimed subject matter, the right-side elevational view (not provided) being a mirror-image thereof;

FIG. 20 is a left side of a bottom plan view thereof split along the dot-dash match line, and with a portion of the unclaimed subject matter cut away to prevent visual obstruction of the claimed subject matter; and

FIG. 21 is a right side of a bottom plan view thereof split along the dot-dash match line, and with a portion of the unclaimed subject matter cut away to prevent visual obstruction of the claimed subject matter.

FIG. 22 is a front, right-side, top perspective view of a fourth embodiment of the security light with a portion of the unclaimed subject matter cut away to prevent visual obstruction of the claimed subject matter;

FIG. 23 is a front elevational view thereof;

FIG. 24 is a left side of a top plan view thereof split along the dot-dash match line, and with a portion of the unclaimed subject matter cut away to prevent visual obstruction of the claimed subject matter;

FIG. 25 is a right side of the top plan view thereof split along the dot-dash match line, and with a portion of the unclaimed subject matter cut away to prevent visual obstruction of the claimed subject matter;

FIG. 26 is a left-side elevational view thereof with a portion of the unclaimed subject matter cut away to prevent visual obstruction of the claimed subject matter, the right-side elevational view (not provided) being a mirror-image thereof;

FIG. 27 is a left side of a bottom plan view thereof split along the dot-dash match line, and with a portion of the unclaimed subject matter cut away to prevent visual obstruction of the claimed subject matter; and,

FIG. 28 is a right side of a bottom plan view thereof split along the dot-dash match line, and with a portion of the unclaimed subject matter cut away to prevent visual obstruction of the claimed subject matter.

The broken lines depict portions of the security light that form no part of the claimed design. The dot-dash chain lines are match lines used to split views and form no part of the claimed design.
